UNITED STATES PATENT OFFICE.

FREDERICK NEWELL MARTINDALE, OF SPRAGUEVILLE, NEW YORK.

WRENCH.

1,072,479.

Specification of Letters Patent.

Patented Sept. 9, 1913.

Application filed December 21, 1912. Serial No. 738,099.

To all whom it may concern:

Be it known that I, FREDERICK N. MARTINDALE, a citizen of the United States, residing at Spragueville, in the county of St. Lawrence and State of New York, have invented a new and useful Wrench, of which the following is a specification.

The present invention appertains to wrenches, and aims to provide a wrench embodying but a single part or handle provided at its ends with single nut receiving openings, the openings being of such figure or contour as to engage a plurality of various sized nuts, and the engagements of the various nuts being in close proximity to the ends and corners of the wrench, thus enabling the wrench to be applied to various sized nuts without adjusting and in a convenient manner, whether the nuts are in the open and unencumbered or whether they are in corners and close quarters.

It is also the object of the present invention to provide a wrench of the character indicated which may be stamped or punched from heavy sheet metal or other stock and which shall have a broad field of service, the same being, especially useful for tightening and loosening nuts in the corners of carriage bodies, chests and the like.

It is known that heretofore wrenches have been provided which are capable of grasping various sized nuts, but it is not known that a wrench has been provided having an opening at each end, the openings being of such figure or contour as to each receive a plurality of various sized nuts that the nuts may be engaged close to and in approximate equal proximity to the end and corners of the wrench.

With the foregoing and other objects in view, which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The preferred embodiments of the present invention have been illustrated in the accompanying drawing, wherein corresponding parts have been indicated by similar reference characters, and wherein:

Figure 1 is a perspective view of one

form of the wrench. Figs. 2, 3 and 4 are plan views of three other variations of the wrench.

Referring specifically to the drawing, the numerals 5, 5^a, 5^b, and 5^c, represent the respective wrenches, each of which is constructed of a flat plate or bar of sheet metal or other stock, preferably in the form of a double or compound curve.

In the form illustrated in Fig. 1, a handle 5 is provided at one end with an opening 6, the inner edge of which is stepped as indicated by the numeral 7, so as to receive a pair of different sized nuts, in order that each nut will be arranged close at an equal proximity to the ends and corners of the wrench. The other end of the wrench or handle is provided with an approximately square nut opening 8 having a lug 9 projecting inwardly from its outer edge and having its side edges each provided with an outwardly facing step as indicated by the numerals 10 and 11 coöperating with the lug to provide supplemental four-sided nut openings, to accommodate various sizes of nuts. The latter opening is so designed that each of the nuts may be grasped on all four sides, this being of advantage for the reason that the wrench when applied to a nut will be held firmly in position and will not fall from the nut when the hand is removed from the handle.

In the form shown in Fig. 2, the wrench or handle 5^a is provided with an opening 6^a at one end, the inner edge of the opening being stepped as indicated by the numeral 7^a so as to receive and grasp three different sizes of nuts, while the other end is provided with an opening 8^a for receiving one or two sizes of nuts.

In the form illustrated in Fig. 3, one end of the handle or wrench 5^b is provided with an opening 6^b, the inner edge of which is stepped as indicated by the numeral 7^b so as to receive two different sizes of nuts, and the other end is provided with an opening 8^b having a lug 9^b projecting inwardly from its outer edge so as to provide the notches 10^b and 11^b. The notches 10^b and 11^b are each adapted to receive a different sized nut, whereas the opening itself is adapted to receive a larger size of nut.

The handle or wrench 5^c shown in Fig. 4, is provided with the respective openings 6^c and 6^d at its ends, the inner edges of the respective openings being stepped as indi-

cated by the numeral 7^c and 7^d so that each opening is adapted to receive two or more different sized nuts, in order that the nuts will be arranged close to and in equal proximity to the ends and corners of the wrench.

In all of the forms, it will be noted that the handles are each provided with a single opening at each end, the openings being of such configurations or contours as to receive 10 and grasp a plurality of various sized nuts at like distances from the end, and corners, thus, the wrenches may be conveniently employed for tightening and loosening nuts in the corners of carriage bodies and chests 15 and in other close quarters, as well as for ordinary purposes. There is no adjusting of the wrench necessary to accommodate the various sized nuts and the openings are so disposed that the wrench may be readily 20 turned without the ends thereof encountering parts adjacent the nut, as when the wrench is employed for tightening or loosening the nut in the corner of a carriage body, chest or the like. The present 25 wrenches are therefore especially useful for

tightening or loosening nuts in corners or close quarters, but are also useful for ordinary purposes, as well.

It is to be noted that each wrench is provided with but a single opening in each end, 30 this being desirable and providing for a compact arrangement so as to accomplish the results aimed at.

Having thus described the invention what is claimed as new is:—

A wrench handle provided with an approximately square nut opening at one end having a lug projecting inwardly from its outer edge, the side edges of the opening each having an outwardly facing step co-operating with the lug to provide supplemental four-sided nut openings.

In testimony that I claim the foregoing as my own, I have hereto affixed my signature in the presence of two witnesses.

FREDERICK NEWELL MARTINDALE.
